UNITED STATES PATENT OFFICE

DONALD B. TOLLEY, OF MACOMB, ILLINOIS, ASSIGNOR TO AMERICAN STEEL PRODUCTS CO., OF MACOMB, ILLINOIS, A CORPORATION OF ILLINOIS

OIL-BURNING BROODER

Application filed November 8, 1928. Serial No. 317,927.

My invention relates to an oil-burning heater of the general class in which the combustion gases pass through a hollow heat-radiating drum before reaching the flue.

Heaters of this class have heretofore been arranged so that the combustion gases circulate once around the inner wall of an annular drum, but in practice this single passage does not afford a sufficiently long contact of the hot gases with the outer wall of the drum to radiate any large proportion of the heat of the gases, so that an undesirably large percentage of this heat passes up the flue. Moreover, with a drum of any considerable height, the hot gases will traverse the annular drum chamber with a spiral movement in which they only impinge against a small portion of the outer wall of the drum.

To increase the heat radiation, it has heretofore been proposed to use a two-story annular drum with the hot gases circulating consecutively in the same direction within the lower and upper stories or annular chambers of this drum. Even this double passage does not insure sufficient heat radiation through the outer drum wall to afford a heater of high efficiency. On the other hand, attempts to use an annular drum with more than two superposed chambers have been found impractical, since the flue draft is usually insufficient for drawing the gases through more than two superposed annular chambers.

What is more, a double circulating of the hot gases within the drum in the same direction along substantially the entire periphery of the drum introduces the objection that one side of the drum (namely that at which the gas inlet, the flue and the connection between the two superposed chambers of the drum are located) is considerably hotter than the opposite side, so that the radiation of heat from the exterior of the drum is not distributed with even an approximate uniformity around the drum. This lack of uniformity is particularly disadvantageous when such a heater is used as part of a brooder for warming quite young (and hence delicate) chicks.

My present invention aims to overcome the

first of these objections by providing an annular heater drum in which the hot gases will circulate partly in one direction and partly in the opposite direction circumferentially of the drum. Moreover, my invention provides a heater construction which will enable even a short flue pipe to afford ample draft for drawing the gases through more than two superposed annular chambers even when the barometer is low.

A further objection encountered with annular drum types of heaters when used in chicken brooders lies in the undue heating of the drum bottom over which the hot gases initially pass. Since this drum bottom is relatively close to the chicks (which can huddle or pass under it when the drum is raised from the floor in the usual manner), the downward heat radiation may be too intense for delicate chicks.

My invention aims to overcome this objection also by providing a drum type heater in which the heated gases pass through the lower story or annular chamber of the drum only after they have first circulated through a more elevated chamber so as to have their temperature reduced by the outward radiation of heat from the more elevated chamber.

Another objection encountered with multi-storyed annular drums in heaters has been the difficulty of cleaning the annular chambers, so as to remove deposits of soot or the like which seriously diminish the heat radiation. Heretofore, it has been customary to provide a side door for access to each chamber, but with such a door opened, the user cannot readily reach the entire interior of the annular drum and hence is unable to keep the drum chambers clean. Besides, the providing of suitably curved doors together with the needed hinges and latches adds considerably to the cost and, unless such doors are carefully fitted, may permit gases to escape and poison the chicks. My present invention aims to overcome these objections by providing a construction which will permit the entire inner wall of a multi-storyed annular drum together with the top closure for this inner wall to be removed bodily, thereby affording the needed access to all interior portions of the drum while per-

mitting the use of a permanently closed outer drum wall.

Moreover, my invention provides a heater in which the needed draft can readily be obtained when the heating member (such as an oil burner) is disposed entirely within the drum and above the bottom of the latter, and one which the flue draft is enhanced by direct heat applied to a portion of the collar of the flue pipe.

Still further and also more detailed objects will appear from the following specification and from the accompanying drawings, in which

Fig. 1 is a central and vertical section through an oil-burning brooder embodying my invention, with a portion of the hood or hover broken away.

Fig. 2 is a plan view of the same, taken from below the hover, with dotted lines indicating the ports in the upper and lower horizontal partitions and also indicating the two vertical partitions or baffles.

Fig. 3 is a central and vertical section through the detached inner drum wall and the top casting which includes the flue collar.

Fig. 4 is an enlarged central and vertical section through the complete drum, taken at right angles to the section of Fig. 1.

Figs. 5, 6 and 7 are reduced horizontal sections taken respectively along the correspondingly numbered lines in Fig. 4, with arrows showing the direction in which the gases circulate in the corresponding chambers.

Fig. 8 is a diagram (in perspective) showing the path of the gases from the burner through the three superposed annular chambers of the drum to the flue.

In the illustrated embodiment, my oil-burning brooder includes spaced legs 1 supporting both the bottom 2 of a hollow drum and the inturned lower ends of the outer tubular wall 3 of this drum. The bottom 2 extends across the bottom of the inner tubular wall 4 and has suitable apertures for admitting air to an oil burner supported by this bottom, this burner being designated generally by the numeral 5 and being here shown in the type disclosed in the copending application No. 314,866, filed October 25, 1928, of William Dow Harvey on an oil burner.

The upper end portion 3A of the outer wall 3 has a casting 6 seated on it, which casting has a central combustion chamber normally closed by a detachable lid 7 and also includes a flue collar 8 fitting the flue pipe 9 of the brooder. Extending above the said casting and lid is the top or canopy 10 of a hover 11 which flares downwardly and outwardly beyond the upper portion of the hollow drum. (The means for supporting this hover are not illustrated, since they form no part of my present invention.)

To permit this hover to come relatively close to the upper end of the drum, I desirably

have the upper end portion 3A of the outer drum wall turned inwardly, as shown in Figs. 1 and 4. The annular drum space (namely, the space between the said inner and outer walls 3 and 4 above the bottom 2 and below the inturned upper end portion 3A) is divided into three stories by a lower horizontal partition 12 and an upper horizontal partition 13. Each of these annular and horizontal partitions is desirably formed of a flat ring of sheet metal having vertical flanges at both its inner and outer edges, and the outer flange 14 on each ring may be fastened (as by welding) to the outer drum wall 3. The inner flange 15 on each horizontal partition slidably fits over the inner drum wall 4 but is not fastened to the latter.

The combustion chamber wall 4 has an outlet 16 for the products of combustion disposed between the two horizontal partitions and below the flue collar 8, and the oil burner desirably includes a flame spreader 5A arranged for cooperating with the draft of the burner to direct the issuing flame against the combustion chamber wall above the lower partition 12. The second or intermediate annular chamber (between the two horizontal partitions) is divided into halves by two vertical baffles 17 and 18, the former (17) being adjacent to one lateral edge of the outlet 16.

The top annular chamber has a vertical baffle 19 at one side of the flue collar 8, and the upper partition (which forms the bottom for this top chamber) has a port 20 at the opposite side of the baffle 19 from the flue collar. The lower partition 12 has two ports 21 and 22 respectively at opposite sides of the baffle 18 which is on the opposite side of the drum from the outlet 16, and the lowest annular chamber is intercepted directly below the baffle 18 by a vertical and also radial baffle 23. Each of the several baffles is preferably fastened to the adjacent partition, so that the baffles rigidly support the partitions in horizontal positions, and each baffle may also be secured (as by welding) to the outer drum wall. So also, the lowest baffle may be secured to the drum bottom.

With the parts thus constructed and arranged, the hot gases of combustion first enter the intermediate annular chamber through the outlet 16 and then pursue the paths indicated by the arrowed lines in Figs. 5 to 8, as follows:

(A) Counterclockwise half way around the intermediate chamber.

(B) Down through the port 21 and clockwise around the bottom chamber.

(C) Up through the port 22 and counterclockwise half way around the intermediate chamber, through the opposite half of the intermediate chamber or section from the initial traversing indicated as A.

(D) Up through the port 20 and clockwise

around the top chamber, then up and out through the flue collar 8 to the flue pipe 9.

As the result of this arrangement for the path of the combustion gases, these lose some of their heat while traversing the initial half of the intermediate chamber, so that the bottom chamber (which is nearest to the chicks) is not so hot as the intermediate chamber or section, and the gases make substantially three entire circuits adjacent to the outer wall 3 of the drum. The heating of the inner wall from the flames and hot gases within the combustion chamber, in which these gases tend to rise by convection toward the top of the drum, also aids in heating the upper chamber, thus intensifying the tendency of the gases within this upper chamber to rise into the flue.

This tendency is further enhanced by my employing a part of the flue collar 8 as a portion of the inner wall of the annular drum, and all the more so when the lower portion of this collar projects radially inward into the combustion chamber as shown in the drawings. Consequently, I can readily secure a sufficiently strong draft, even with a short flue pipe and a low barometric condition, to draw the combustion gases through the drum in a circuitous path in which these gases flow downward during a part of their travel, although convection would urge them upwardly.

Moreover, the combustion gases while traversing both halves of the intermediate chamber move in the opposite direction (circumferentially of the drum) with respect to those in both the bottom and the top chambers. Hence I secure a better equalization of the temperature circumferentially of the drum than can be obtained with the now customary hollow drum heaters in which the combustion gases continuously move in one circumferential direction.

To afford access to the burner, I provide a canopy lid 24 directly over the drum lid 7 as a detachable portion of the canopy top of the hover. The entire canopy is preferably arranged so that it can be lifted off when the drum is to be cleaned, after which the bolts 50 26 (Fig. 4) which secure the casting 6 to the outer drum wall are detached. The unit consisting of the inner drum wall 4 and the flue collar 8 can then be lifted out of the drum as the unit shown in Fig. 3, thereby affording 55 access to the three superposed chambers of the drum without requiring doors which would increase the cost and which would not afford ready access at both sides of each baffle. This provision also enables me to 60 employ an entirely imperforate outer drum wall, thereby avoiding gas or smoke leaks which might seriously affect the chicks.

The vertical baffles, which desirably have their outer edges turned (as shown in Figs. 65 5 to 7) and secured to the outer drum wall,

aid in rigidly supporting the two horizontal partitions, so that the latter retain their flat shapes although not fastened at their inner ends to the inner drum wall 4. Hence the removability of the above mentioned unit does not prevent my providing a rigid assembly which will readily withstand rough handling both in transit and in use. By providing these baffles with flanges along all four edges, I can readily secure an adequate seal at these edges to avoid any appreciable leak 75 age past the baffles.

Owing to the effective draft secured in my heater, I can also dispose the oil burner entirely within the drum, instead of having it 80 considerably lower where the intensity of its direct laterally radiated heat might injure some of the chicks, and I save the expense of an additional lower chamber for housing the burner.

However, while I have illustrated and described my invention in a heater designed for use as part of a chicken brooder, I do not wish to be limited to the purpose for which my heater is employed. Neither do I wish to be limited to the details of the construction and arrangement above described, since changes might obviously be made without departing either from the spirit of my invention or from the appended claims.

I claim as my invention:

1. A heater comprising an annular drum having an outlet adjacent to its top, annular partitions dividing the hollow drum into superposed chambers, a heating device within the combustion chamber, an outlet in the combustion chamber wall, ports in the partitions, and upright and substantially radial baffles extending from the inner to the outer drum wall; the baffles being so arranged with respect to the ports, and the first named outlet as to compel the combustion gases from the heating device to flow within the drum in a circuitous path in which the gases flow circumferentially of the drum in opposite directions in two superposed sections.

2. A heater comprising an annular drum having an outlet adjacent to its top, annular partitions dividing the hollow drum into superposed chambers, a heating device within the combustion chamber, an outlet in the combustion chamber wall, ports in the partitions, and upright and substantially radial baffles extending from the inner to the outer drum wall; the baffles being so arranged with respect to the ports, and the outlets as to compel the combustion gases from the heating device to flow within the drum in a circuitous path in which the gases flow through a portion of one section before flowing through a relatively lower section.

3. A heater comprising an annular drum having an outlet adjacent to its top, annular partitions dividing the hollow drum into superposed chambers, a heating device with-

- in the combustion chamber, an outlet in the combustion chamber wall, ports in the partitions, and upright and substantially radial baffles extending from the inner to the outer drum wall; the baffles being so arranged with respect to the ports, the first named outlet as to compel the combustion gases from the heating device to flow within the drum in a circuitous path in which the gases flow consecutively through a portion of the intermediate section, then through the lowest section, next through another portion of the intermediate section, and last through the top section.
15. 4. A heater comprising a hollow drum having an outlet adjacent to its top and an outlet in its combustion chamber, annular horizontal partitions subdividing the annular space between the inner and outer walls of the drum into superposed annular sections, and substantially radial baffles extending within the said sections, the baffles being provided with ports so disposed with respect to the baffles as to compel gases to traverse all of the said sections in flowing from the combustion chamber outlet to the first named outlet; and a top member normally closing the upper end of the hollow drum, the inner wall of the drum being fastened to the top member and slidably fitting the inner edges of the partitions.
5. A heater as per claim 4, in which the top member includes a flue collar having a portion thereof effectively forming part of the inner wall of the hollow drum.
6. A heater as per claim 4, in which the top member includes a flue collar projecting radially into the combustion chamber of the drum below the top of the drum.
40. 7. A heater as per claim 4, in which each baffle is secured at its outer edge to the outer drum wall and has at its inner edge a flange slidably engaged by the inner drum wall during the assembling of the heater.
45. 8. A heater comprising an annular drum having an outlet adjacent to its top and an outlet in its combustion chamber, annular horizontal partitions subdividing the annular space between the inner and outer walls of the drum into superposed annular sections, and substantially radial baffles extending within the said sections, the baffles being provided with ports so disposed with respect to the baffles as to compel gases to traverse all of the said sections in flowing from the combustion chamber outlet to the first named outlet; and a heating device disposed within the combustion chamber and having its heat-emitting portion below the said inlet.
50. 9. A heater comprising an annular drum and two vertically spaced annular horizontal partitions dividing the annular space between the inner and outer walls of the drum into three superposed sections; the upper section having an outlet, and the intermediate sec-

tion having an outlet in the inner drum wall in substantially vertical alignment with the first named outlet; a first upright baffle extending radially across the upper section between the two drum walls at one side of the outlet, two upright baffles extending radially across the intermediate section at opposite sides of the inner drum wall between the inner and outer drum walls in substantially the same vertical plane with the baffle in the upper section, and a fourth upright baffle extending radially substantially in the said plane between the inner and outer drum walls across the portion of the bottom section which is at the opposite side of the drum from the outlet; the upper annular partition having a port on the opposite side of the first named baffle from the outlet; and the lower annular partition having two ports respectively at opposite sides of the fourth partition.

10. A heater including a bottom plate provided near its center with an air inlet, two radially spaced drum walls supported by the bottom plate and having a common vertical axis, a drum top member supported by the outer drum wall and having an outlet port therein, a burner supported above and near the bottom plate, and annular horizontal and vertically spaced partitions dividing the annular space between the inner and outer drum walls into superposed chambers; in combination with radial and upright baffles in the said chambers, ports in the partitions, and an outlet port in the inner wall above one of the partitions, substantially as and for the purpose described.

11. A heater as per claim 10, in which the partitions and baffles are secured and substantially sealed both to each other and to the outer drum wall; the partitions and baffles all extending close to but being unsecured to the inner drum wall, so as to permit the removal of the latter.

12. A heater comprising an annular drum having an outlet port adjacent to its top and a second port in its inner wall above the bottom of the drum; closures for both ends of the drum, a heating device within the combustion chamber and below the said second port, two vertically spaced annular partitions dividing the space between the inner and outer drum walls into superposed chambers, vertical and substantially radial baffles subdividing the chambers, and partition ports in the partitions adjacent to the baffles; the partition ports being so disposed as to compel the combustion gases from the heating device to traverse a portion of an intermediate section before passing through either the lower or the upper section.

13. A heater as per claim 12, including a flue collar associated with the outlet port and presenting a wall portion within the combustion chamber to direct heat from the heating device, whereby the direct heating of the flue

collar augments the draft through the outlet port.

14. A heater as per claim 12, in which the heating device is a burner constructed for directing its flame against the combustion chamber wall below the top of the outlet.

15. A heater including an outer drum wall, a bottom plate extending across the lower end of the said wall and secured to the latter, a combustion chamber wall of smaller diameter than the outer drum and loosely seated on the bottom plate, a top member normally closing the upper end of both drum walls and detachable from the outer drum wall but fastened to the combustion chamber wall; and a perforate annular partition extending horizontally between the inner and outer drum walls and secured only to the latter, the partition being freely spaced from the bottom plate and the top member.

16. A heater as per claim 15, in which the top member includes a detachable lid disposed for affording access to the space within the combustion chamber wall.

25 Signed at Macomb, Illinois, October 27th, 1928.

DONALD B. TOLLEY.
